ATTORNEY

WITNESS:

UNITED STATES PATENT OFFICE.

WILLIAM JAMES MILLER, OF GOOSE CREEK, TEXAS.

CALIPERS.

1,411,929.

Specification of Letters Patent.

Patented Apr. 4, 1922.

Application filed February 23, 1921. Serial No. 447,189.

To all whom it may concern:

Be it known that I, WILLIAM J. MILLER, a citizen of the United States, residing at Goose Creek, in the county of Harris and 5 State of Texas, have invented new and useful Improvements in Calipers, of which the following is a specification.

This invention relates to improvements in calipers, the principal object of the invention being to provide one arm of the calipers with a steel tape so arranged that the distance between the ends of the arms can be measured by said tape.

Another object of the invention is to provide means whereby the tape can be carried in rolled condition in the calipers when not in use.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is an elevation of the invention showing the tape in partly extended position.

Figure 2 is a sectional view through the tape carrying arm of the calipers.

35 Figure 3 is a section on line 3—3 of Figure 1.

Figures 4 and 5 are detail views.

40 Figure 6 is a sectional view through that part of the hollow arm which carries the spool.

In these views A indicates the calipers which are constructed in the more ordinary manner excepting that one arm is made of considerable width and is provided with 45 a chamber 1 intermediate its ends and a slot 2 which extends from the chamber through the free end of the arm. Side plates 3 are secured to the arm by the screws 4, these plates covering the chamber and the major portion of the slot. A spool 5 is journaled in chamber 1 by means of the screw bolt 6 passing through the spool and the plates 3. This spool supports the tape 7 which is preferably made of steel and said tape 55 is kept wound upon the spool by means of the coil spring 8. The free end of the

tape is provided with a part 9 which may be welded thereto and which acts as a thumb hold and as a stop for engaging the end of the calipers arm for preventing the 60 outer part of the tape from being drawn through the slot and upon the spool. By placing the thumb against this projecting part the tape can be unwound from the spool and drawn through the slot. 65

I also provide means for holding the tape in its adjusted position or partly withdrawn from the slot, such means consisting of a thumb screw 10 rotatably mounted in the small end of the calipers adjacent 70 the slot and having a flat part 11 which can be brought in alignment with one wall of the slot so as to permit free movement of the tape but when the screw is turned the rounded part will press the tape against the 75 upper wall of the slot and thus clamp the same and prevent the spring spool from drawing the tape inwardly.

It will thus be seen that the tape can be used in measuring the distances between the 80 ends of the calipers arms, the thumb screw 10 holding the tape in its adjusted position so that the user can readily read the figures on the tape. Of course the tape can be used for measuring other distances if 85 desired.

I prefer to use a tape marked as indicated in Figure 5 which shows the central part of the tape left blank but with the lines separating the inches passing entirely 90 across the face of the tape. This blank central space is engaged by the end of the calipers arm.

It is thought from the foregoing description that the advantages and novel features 95 of my invention will be readily apparent.

I desire it to be understood that I may make changes in the construction and in the combination and arrangement of the several parts, provided that such changes 100 fall within the scope of the appended claims.

What I claim is:—

1. Calipers having pivoted arms, one of which is hollow, a spool located in said 105 hollow arm and a graduated tape carried by the spool and adjustable toward the free end of the other arm and through the free end of the hollow arm.

2. Calipers having pivoted arms, one of 110 which is hollow, a spring actuated spool in said hollow arm and a graduated tape on

the spool adjustable toward the free end of the other arm and through the free end of the hollow arm.

3. Calipers having pivoted arms, one of which is provided with a chamber and a longitudinally extending slot, said slot passing through the free end of the arm, side plates for closing said chamber and slot, a

spring actuated spool in said chamber, a graduated tape carried by the spool and 10 passing through the slot, a stop at the free end of the tape for engaging the end of the arm and means for holding the tape in adjusted position.

In testimony whereof I affix my signature.
WILLIAM JAMES MILLER.
